UNITED STATES PATENT OFFICE.

CHARLES F. HILL, OF JANEVILLE, WISCONSIN.

BOOKBINDING DEVICE.

1,212,352.

Specification of Letters Patent. Patented Jan. 16, 1917.

Application filed September 21, 1914. Serial No. 962,649.

To all whom it may concern:

Be it known that I, CHARLES F. HILL, a citizen of the United States, residing at the city of Janesville, county of Rock, and State of Wisconsin, have invented new and useful Improvements in Bookbinding Devices, of which the following is a specification.

The object of my invention is to provide a simple and efficient device adapted to be used by amateurs in school, or elsewhere, to do their own bookbinding and repairing, and it pertains more especially, among other things: A, to the device for retaining the leaves of a book in their proper relative position to each other preparatory to and while being clamped between the jaws of a vise; B, to the construction of the vise; C, to the construction of the clamping plates which are adapted to be attached to the jaws of the vise, said plates being provided with a series of guide notches; D, to the creasing plates which are adapted to be slidably secured to the clamping plates, and, E, to the device for holding the book at the desired elevation between the clamping plates.

My invention is further explained by reference to the accompanying drawings, in which—

Figure 1 represents a front view of the vise provided with a pair of notched clamping plates. Fig. 2 is a vertical section drawn on line α , α of Fig. 1. Fig. 3 is a front view of the upper portion of the vise provided with both clamping and creasing plates. Fig. 4 is a side view of the device shown in Fig. 3, showing the book in place between the clamping jaws of the vise. Fig. 5 is a perspective view of the device used for supporting the book preparatory to and while the same is being clamped in the vise, and, Fig. 6 is a perspective view of one of the creasing plates.

Like parts are identified by the same reference numerals throughout the several views.

The vise comprises, among other things, two vertical boards 1 and 2, which are secured together by the hand actuated clamping screws 3, 3. The board 2 is provided

with recesses 4, 4 for the reception of the nuts 5, which recesses are rectangular in shape conforming in shape to the nuts, whereby such nuts are prevented from turning with the clamping screws 3. The nuts 5, 5 are retained in place by the plates 6, 6. The board 1 is provided with recesses 7, 7 for the reception of the collars 8, 8, and said collars 8 are rigidly fixed to the clamping screws 3. Said recesses 7 being circular in shape to conform to the shape of the collars, and said collars and nuts are retained in said recesses by the plates 6 and 9. All of said plates are retained in place by screws 11. Preparatory to placing the book between the jaws 13 of the vise, such book is placed between the resilient plates 14, of the book holder; said plates 14, 14 are preferably formed integral, being connected together at their lower edges by the transverse member 15.

16 is a block preferably made of wood and it is secured to the member 15. The upper side of the block 16 is convex and is adapted to give the front edge 17 of the book the required concave shape, whereby the back of the book 18 is given the ordinary convex shape shown in Fig. 2.

A pair of notched clamping plates 19, 19 are rigidly secured to the jaws 13 of the vise by a pair of clamping bolts 20, 20. After the book has been placed between the resilient members 14, of the holder, it is placed between the clamping plates 19, as shown in Fig. 2, the lower edge of the holder resting upon the supporting screw 21, as shown in Figs. 2 and 4. The screws 21 are formed integral with and at right angles to the screws 22, and the same are adjusted at the required elevation within the vertical slots 23, 23 by the nuts 24, 24 operating on the screws 22. The nuts 24 on the screws 22 are supported by the angular brackets 25, which brackets 25 are formed integral with the vertical plates 9. Thus it is obvious that by turning down the nuts 24 on said screws 22 said screws will be raised, while by the reverse movement of said nuts, said horizontal screws 21 will be lowered.

The screws 21 are retained in the horizontal position at right angles to the members 1 and 2 of the vise by the nuts 26, which nuts 26 are adapted to bear against 5 the front surface of the member 1 upon the respective sides of the slots 23. A screw thread is formed on the horizontal member or screw 21 for the reception of the nut 26. Thus it will be obvious that by turning forward 10 said nuts 26 the ends of said screws 21 will be raised, while by turning them back they will be lowered, said nuts 26 being adjusted so as to retain said screws 21 in the horizontal position beneath the book while 15 said screw is raised and lowered by turning the nuts 24 downwardly and upwardly, whereby the back of the book is brought on substantially the same plane as the upper edge of the clamping plates 19. When 20 the book has been thus adjusted it is securely clamped between the clamping plates 19, 19 by turning forwardly the screws 3, 3. This being done a series of notches are filed 25 or otherwise cut in the back of the book corresponding with the guide notches 27 formed in the upper edges of the plates 19, 19. Said notches 27 serve to guide the file or other instrument while cutting the notches in the back of the book. A binding cord is then 30 inserted in the notches of the book and a quantity of glue is placed upon the edges of the book whereby the leaves of the book are securely held in place. When this is done the book is taken out of the vise and an additional quantity of glue is placed above the 35 binding cord and the cover 28 of the book is then put in place upon the leaves when the book is again placed between the clamping jaws of the vise. Before placing the book a second time between the jaws of the 40 vise the creasing plates 29, shown in Fig. 6, are secured to the clamping plates 19, as shown in Figs. 3 and 4, when the jaws of the vise are again brought together by 45 turning forward the clamping screws 3, whereby the angular flanges 30, of said creasing plate, are forced firmly against the respective sides of the cover of the book, thereby forming the creases 31, 31 in the 50 cover and the body of the book, whereby the cover is permanently secured to the book. The creasing plates 29 are provided at their respective ends with the U shaped loop members 32, 32, which are adapted to be slid 55 down over the ends of the clamping plates 19, as shown in Fig. 3, while the upper edges of said clamping plates are also preferably provided with U shaped bends 33, 33, which are adapted to engage the upper edge 60 of the clamping plates and retain said creasing plates in their proper relative positions to said clamping plates as they are being used, and as shown in Fig. 3 of the drawing. The member 1 of the vise is supported

from the member 2 by the angular brackets 65 34, 34 and 35, 35. The angular brackets 34 are rigidly secured to the member 2 by the screws 36 while the brackets 35 are secured to the member 1 by the screws 37, 37, whereby the upper ends of the members 1 and 2 70 are always retained upon the same plane.

Having thus described my invention, what I claim as new, and desire to secure by Letters Patent, is—

1. In a device of the described class, the 75 combination of a pair of vertical clamping members connected together by a plurality of screws, a pair of clamping plates, each plate being provided at its upper end with a series of guide notches, means securing 80 said clamping plates to said vertical members, and means for moving said vertical members toward and from each other.

2. In a device of the described class, the 85 combination of a pair of vertical clamping members, a pair of clamping plates each plate being provided at its upper edge with a series of guide notches, means securing said clamping plates to said vertical members, means for moving said vertical members toward and from each other, a pair of creasing plates, and means for temporarily 90 securing said creasing plates to said clamping plates.

3. In a device of the described class, the 95 combination of a pair of vertical members, a plurality of clamping screws connecting said members together, a pair of clamping plates secured to said vertical members, each clamping plate being provided at its upper 100 edge with a series of guide notches, a book-holder, and means for supporting said book-holder at different elevations between said clamping plates.

4. In a device of the described class, the 105 combination of a pair of vertical members each provided with two elongated slots for the reception of adjustable book supporting members, book supporting members, means for adjustably holding said book supporting members at any desired point of adjustment in said slots, a book holder for holding the book while being sewed, said book supporting members being adapted to be raised and lowered according to the width of the book 110 being bound, a pair of notched clamping plates adapted to be supported from the upper ends of said vertical clamping members.

5. A bookbinding vise comprising two vertical clamping members, each provided with a plurality of vertical slots, means for supporting the upper ends of said clamping members in the same plane, an angular bracket affixed to the front side of one of said clamping members, an angular member 120 comprising two screws connected together at right angles to each other, one of said screws 125 being adjustably supported in said vertical

slots and the other screw adjustably supported upon said angular bracket, a pair of horizontally arranged screws, means for retaining the horizontal member of said screws in a horizontal position, and means for adjusting and retaining said horizontal screws at a lower or higher plane in said slots, a pair of clamping screws revolubly support-

ed from near the lower end of said clamping members. 10

In testimony whereof I affix my signature in the presence of two witnesses.

CHARLES F. HILL.
